[57] CLAIM

The ornamental design of a pistol grip with funnel well and thumb guard, as shown and described.

DESCRIPTION

FIG. 1 is a side elevational view of the pistol grip for one side of a pistol showing my new design; an elevational view of the pistol grip of the opposite side of a pistol being a mirror image of FIG. 1;

FIG. 2 is a front elevational view of the pistol grip of FIG. 1 looking from the right of FIG. 1;

FIG. 3 is a rear elevational view of the pistol grip of FIG. 1 looking from the left of FIG. 1;

FIG. 4 is a top plan view of the pistol grip of FIG. 1;

FIG. 5 is a bottom plan view of the pistol grip of FIG. 1; and,

FIG. 6 is a rear elevational view of the pistol grip of FIG. 1.

The partially cross-hatched portions of FIGS. 1, 2, 3, and 4 represent knurling of the pistol grip.
